UNITED STATES PATENT OFFICE.

HORACE GREENING, OF DORCHESTER, ENGLAND.

COLLAPSIBLE BOX.

1,377,678.

Specification of Letters Patent. Patented May 10, 1921.

Application filed May 12, 1919. Serial No. 296,586.

To all whom it may concern:

Be it known that I, HORACE GREENING, a subject of the King of England, residing at Dorchester, in the county of Dorset, England, have invented certain new and useful Improvements in or Connected with Collapsible Boxes, of which the following is a specification.

This invention relates to collapsible boxes to be used as packing cases for commercial and other purposes, and has for its object to provide a simple construction of box wherein the sides and ends will fold over the bottom, and the cover be fixed over them, so as to collapse the box into a small compass for "returned empty" carriage or the like.

A collapsible box according to my invention comprises a bottom part to which are hinged the two side parts and two end parts, the side parts being adapted to fold one over the other on the bottom part, and the end parts being adapted to fold over the two side parts. The lid is adapted to be placed and fastened over the above folded parts so as to provide a compact portable arrangement of the parts in a small compass. In an open position the side parts are fastened by means of sliding locks to the end parts, and when the lid or cover is placed on, it is also locked to the end parts, thereby providing a secure fastening when the box is closed. This locking device is provided on one of the end parts by means of which the lid may be locked on the box, and the lock is then covered by a direction label which prevents the lock being tampered with.

In order to make my invention clearly understood I refer to the accompanying drawings, in which:

Figure 1 shows the box in side perspective elevation with the front side thrown back;

Figs. 1^A, 1^B, and 1^C show the sliding lock in detail;

Fig. 2 shows a side view of the box collapsed;

Fig. 3 shows a plan of the box collapsed, with the lid on;

Fig. 4 shows a plan of the box collapsed, with the lid off;

Fig. 4^A shows the locking pin for the lid in detail;

Fig. 5 shows a plan view of the box with the ends raised;

Fig. 6 shows a plan view of the box with the ends and sides raised, and

Fig. 7 shows a perspective drawing of a deep and narrow box.

With reference to the drawings, *a* designates the bottom part of the box, *b*, *b*¹ denote the side parts respectively, and *c*, *c*¹ denote the end parts. The side part *b* is hinged at *d* to the bottom part *a*, as shown in Fig. 1, so that it will turn down and lie flat on the said bottom part, and the side part *b*¹ is hinged to a bar *a*¹ on the bottom part *a*, so that when it is turned down it will lie flat over the turned-down side part *b*. In like manner the end parts *c*, *c*¹ are hinged at *d*¹, *d*¹ to the raised parts *e*, *e*¹ at the ends of the bottom *a* so that when they are turned down they lie flat over the side parts *b*, *b*¹, as shown in Fig. 4. The side parts *b*, *b*¹ are secured at the respective corners to the end parts *c*, *c*¹ by means of slide catches *f* with bent-over parts *f*¹ provided on the said side parts and adapted to engage with screw heads *h*² provided on the corner parts *c*², by which means the box parts are securely attached together.

These slide catches *f* are shown in an engaged position in Figs. 1^A, 1^B, and in a disengaged position in Fig. 1^C. Each of the slide catches *f* is mounted in a recess *r* cut in the side parts so that the corresponding faces of the said catches and the side parts are flush. The catches are moreover guided by clips or guide plates *p*, the catches being formed with undercut key hole slots *f*² and the clips with holes *f*³ in such a manner, that the screw heads *h*², when the side parts are raised for fixing purposes, are made to project through the holes *f*³ and the circular portion of the key hole slots *f*². To secure the side parts in this position it is then merely necessary to slide the catches, the screwed part of the screw head *h*² thus being caused to engage the narrow part of the key hole slot *f*². The disposition of the screw heads and the slide catches is more clearly shown in Fig. 5.

The bent-over parts *f*¹, when the side parts are secured to the corner pieces *c*², are engaging with the top of the latter and held in position by the cover of the box so that accidental displacement of the catches is prevented. *g* denotes the cover or lid which is adapted to be placed over the box and fas-

tened by means of devices similar to that already described and comprising undercut key hole slots g^1 and undercut grooves g^2 , shaped respectively on the underside of the cover g as shown, and adapted to engage with the screw heads h^2 on the end parts c , c^1 as the cover is slid over. That is to say, the cover is secured to the box by sliding it in the direction of the arrow, Fig. 3, the screw heads h^2 thus being made to lie in the circular portion of the slot g^1 and the undercut grooves respectively, and preventing detachment of the cover other than by a sliding movement in a direction opposite to that indicated by the arrow.

h is a locking device of the form shown in Fig. 4^A, comprising a pin which is set in a recessed part h^1 on the end part c , and which can be turned, elevated, and inserted into a hole in the cover. This locking device is then covered, as previously stated, by means of an address label which prevents it from being tampered with.

To collapse the box when the cover has been removed, the catches f are raised by means of the bent-over parts f^1 and the side part b turned down, after which the side part b^1 is turned down to cover the part b . Then the end parts c , c^1 are turned down to lie over the side parts, and the cover is placed in position over the folding parts and secured by other screw heads h^2 which are inserted into holes in the upright bars j , as shown in Fig. 2.

In the case of deep narrow boxes, the side parts b , b^1 are made in two pieces hinged together to enable them to fold down and lie on the bottom, as shown in Fig. 7.

The completed box provides a simple and convenient arrangement, inasmuch as it can be collapsed when required for return transport or otherwise, the parts being easily raised into position to form a suitable receptacle for commercial or other uses.

Having now fully described my said in-

vention what I claim and desire to secure by Letters Patent is:—

1. In the herein described collapsible box in which the side parts and the end parts are provided with corner pieces and hinged to the bottom part so as to be adapted to fold one over the other and over the said bottom part, means for locking the side parts and the end parts to and unlocking the same from each other, the said means comprising a slide catch, and guide plates fitted near the corners and tops of each of the side parts and having undercut key hole slots and holes respectively, and screw heads secured to the aforesaid corner pieces and adapted to engage with the key hole slots in the catches and the holes in the guide plates, all substantially as set forth.

2. In the herein described collapsible box in which the side parts and the end parts are hinged to the bottom part and adapted to fold one over the other and over the said bottom part and wherein one of the end parts is provided with a recess, the combination, with means for locking the side and end parts to each other, of a cover having a hole and undercut key hole slots and undercut cut grooves at its underside, and means for locking the cover to the end parts the said means comprising screw heads secured in the said end parts with which the said slots and grooves are adapted to engage, and a pin which is set in the aforesaid recess of one of the end parts which pin is adapted to be turned, elevated, and inserted into the hole of the cover, all as and for the purpose set forth and shown.

In testimony whereof I have hereunto set my hand in the presence of two subscribing witnesses.

HORACE GREENING.
